UNITED STATES PATENT OFFICE.

THOMAS CALLANAN, OF BROOKLYN, NEW YORK.

IMPROVEMENT IN CORNER-PIECES FOR PICTURE AND OTHER FRAMES.

Specification forming part of Letters Patent No. **138,611**, dated May 6, 1873; application filed
March 15, 1873.

To all whom it may concern:

Be it known that I, THOMAS CALLANAN, of Brooklyn, in the county of Kings and State of New York, have invented an Improved Corner Piece for the Frames of Pictures, Wire-Screens for Windows, and for other articles, of which the following is a specification:

This invention consists in a corner piece for the frames of pictures, window-screens, and the like, composed of a thin web which fits in a saw-kerf made in the meeting-edges of the frame and flanges, which fit, one outside and the other inside, the rails near their junction. By this corner-piece not only are the rails of the frame very securely connected but twisting of the frame itself is prevented.

In the accompanying drawing, Figure 1 is a view of a corner of a window-screen frame having my corner-piece applied. Fig. 2 is a sectional view of the same illustrating the situation of the corner-piece. Fig. 3 is a face view of the corner-piece detached. Fig. 4 is a transverse section thereof taken at the line *x x* in Fig. 3, and Fig. 5 is a like section taken at the line *y y* in the same figure.

Similar letters of reference indicate corresponding parts in all the figures.

A and B represent the meeting portions of two rails of the window-screen frame. They are of the ordinary form, save that in the end of each there is a kerf or slit made for the reception of the web of the corner-piece. This

corner-piece consists of a thin web, *a*, having inner and outer flanges *b* and *c* extending along its side edges. The outer flange *c* fits in a countersink or groove in the edge of the frame, but the inner fits just without the rails, as shown in Fig. 2. These flanges extend beyond the ends of the web, and are secured to the rails of the frame by screws or nails.

The outer flanges of the corner-piece are hidden from view, and so also are the inner flanges when a picture or screen is applied to the frame. When desirable, however, these inner flanges may also be countersunk. The great advantage of this corner-piece of mine is that not only are the rails of the frame secured together in longitudinal and facial directions, but twisting of the frame is obviated. The webs of the corner-pieces fitting tightly within the saw-kerfs in the rail prevent any twisting whatever.

What I claim as my invention and desire to secure by Letters Patent, is—

A corner-piece for the frames of pictures, window-screens, and the like, composed of a thin web, *a*, and flanges *b* and *c*, extending along the edges of the same, substantially as set forth.

THOMAS CALLANAN.
